UNITED STATES PATENT OFFICE.

HAROLD H. WILL, OF SYRACUSE, NEW YORK, ASSIGNOR TO THE WILL & BAUMER CO.,
OF SYRACUSE, NEW YORK, A CORPORATION OF NEW YORK.

DESIGN FOR A CANDLE.

53,404.

Specification for Design.

Patented June 3, 1919.

Application filed August 29, 1916. Serial No. 117,547. Term of patent 14 years.

To all whom it may concern:

Be it known that I, HAROLD H. WILL, a citizen of the United States, residing at Syracuse, in the county of Onondaga and State of New York, have invented a new, original, and ornamental Design for a Candle, of which the following is a specification, reference being had to the accompanying drawing, forming a part hereof.

In the drawing, Figure 1 is a side elevation of a candle of my design.

Fig. 2 is a top plan view thereof.

This design for a candle comprises a base and a shank or body rising from the base, the base having a cylindrical upper part *a*,

and a conoidal lower part *b* tapering downwardly from a point intermediate of the top and bottom of the base and having lengthwise ribs *c* merging at their upper ends into the cylindrical part *a* and lengthwise conoidal surfaces *d* interposed between the ribs *c*.

I claim:

The ornamental design for a candle, substantially as shown and described.

In testimony whereof, I have hereunto signed my name, at Syracuse, in the county of Onondaga, and State of New York, this 9th day of June, 1916.

HAROLD H. WILL.
